UNITED STATES PATENT OFFICE.

WILLIAM C. YERGER OF KINGSPORT, TENNESSEE.

RAZOR-STROP HOLDER.

1,181,197.

Specification of Letters Patent.

Patented May 2, 1916.

Application filed December 13, 1915. Serial No. 66,683.

To all whom it may concern:

Be it known that I, WILLIAM C. YERGER, a citizen of the United States, residing at Kingsport, in the county of Sullivan and State of Tennessee, have invented new and useful Improvements in Razor-Strop Holders, of which the following is a specification.

This invention relates to razor strop holders, and it has for its object to produce a device of this class of simple and of improved and effective construction. Men whose vocations compel them to travel frequently from place to place and who largely patronize hotels are frequently put to great annoyance by the lack or total absence of some convenient place to which a razor strop may be attached while being held in position for stropping a razor. Facilities of this kind are noticeably absent in the Pullman cars and in toilet rooms and lavatories of hotels throughout the country. Razor strops, being by no means of standard manufacture or construction, are, moreover, provided with various attaching means, thereby rendering the problem of a convenient attaching device more vexatious. Thus, some razor strops are provided with small swiveled eyelets. Other strops are provided with eyelets either stationary or swiveled of an oblong shape which, if attached to an ordinary hook, would render the strop liable to become twisted or contorted when pulled to extend the same for operation. Again, some strops are provided with a dovetailed projection adapted to be engaged with a mortise formed in a special supporting or attaching device; but, inasmuch as the latter, when purchased, is usually permanently mounted in the bath room of the home of the pur- chaser while the strop is frequently carried away from home, a device of this kind renders the problem of attaching or supporting the strop when away from home even more troublesome.

The object of the present invention, therefore, may be specifically stated to produce a simple and thoroughly effective supporting device which may be mounted in the lavatories of Pullman cars, in the bath rooms of hotels and in any other places where the use thereof is desired and which will afford a convenient means for attaching and supporting a strop having any kind of supporting device in general use at the present time or likely to be hereafter developed.

With this and other ends in view which

will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing, Figure 1 is a front view of a supporting device constructed in accordance with the invention. Fig. 2 is a top plan view of the same. Fig. 3 is a side elevation. Figs. 4, 5 and 6 are plan views showing portions of razor strops having different attaching and supporting means. Fig. 7 is a top plan view showing a razor strop of the type illustrated in Fig. 6 attached to the improved support.

Corresponding parts in the several figures are denoted by like characters of reference.

The improved device comprises an attaching plate 15 having apertures 16 for the passage of fastening members, such as ordinary headed screws, whereby it may be mounted in position on a wall or similar support. Extending forwardly from the plate 15 is a shank 17, and rising from the forward end of said shank is an upwardly and rearwardly inclined approximately triangular plate 18 having a vertical slot 19. Extending rearwardly from the apex of the plate 18 is a prong 20. The parts are to be so proportioned that while the triangular plate 18 is located in an inclined plane, being inclined upwardly and rearwardly, the terminal of the rearwardly extending prong 20 shall be properly spaced from the wall or object to which the plate 15 is attached to permit the attaching means of a razor strop to be placed in engagement therewith.

The razor strop shown in Fig. 4 is provided with a relatively small eye 21 which, however, may be easily engaged with the prong 20, thus permitting the strop to be stretched and held perfectly taut. If the eye is of materially larger diameter than the prong 20, the act of stretching the razor strop will simply cause said eye to slide downward on the sides of the inclined tri-

angular plate 18 until it comes to rest at a point where the width of the plate is equal to the internal diameter of the eye.

In Fig. 5 has been shown a razor strop, the attaching means of which consists of an oblong eye 22. The manner of mounting such an eye on the device is similar to that already described, it being obvious that by stretching or tautening the razor strop the eye will automatically come to rest at a point where the width of the plate 18 equals the length of the oblong eye 22. The razor strop when tensioned will thus be held securely and without wobbling.

In Fig. 6 there has been shown a razor strop, the attaching means of which consists of a triangular dovetailed plate 23 having a relatively narrow shank portion 24. The plate 23, when held edgewise, may be introduced through the slot 19 until the shank portion 24 reaches the slot, after which by restoring the plate 23 to a horizontal position, it will be held securely against withdrawal, thus permitting the strop to be tensioned.

It will be seen from the foregoing description, taken in connection with the drawing, that it will be difficult to find a razor strop having any kind of attaching means that might not in some convenient manner be engaged with the improved supporting device. The latter may, therefore, justly be held to be universally useful and adaptable to the support of razor strops of all known and conventional makes.

The improved device may be easily and inexpensively made by casting of brass, malle-

able iron or other appropriate material which may be afterward embellished by plating or in any well known way. It is obvious that the precise construction is susceptible of many modifications, and no limitation is, therefore, made to the precise construction herein shown and described.

Having thus described the invention, what is claimed as new, is:

1. A device of the class described comprising a supporting member having a forwardly extending shank, and an upwardly and rearwardly inclined triangular plate carried by said shank and having at the apex thereof a rearwardly extending prong, said plate being also provided with a vertical slot.

2. A universal razor strop supporting device comprising a vertically slotted triangular plate having at the apex thereof a rearwardly extending prong, said plate being supported in an upwardly and rearwardly inclined position by a supporting member having means for attaching it to a wall or the like, the parts being so proportioned that when the device is mounted in position for operation the terminal of the prong at the upper end of the inclined triangular plate shall be spaced from the wall or object on which the device is mounted.

In testimony whereof I affix my signature in presence of two witnesses.

WILLIAM C. YERGER.
